United States Patent Office.

JOHN H. ELWARD, OF PALO, ILLINOIS.

Letters Patent No. 94,092, dated August 24, 1869.

IMPROVED WASH-BOILER.

The Schedule referred to in these Letters Patent and making part of the same.

To all whom it may concern:

Be it known that I, JOHN H. ELWARD, of Palo, in the county of Ogle, and State of Indiana, have invented a new and useful Improvement in Wash-Boilers; and I do hereby declare that the following is a full, clear, and exact description thereof, reference being had to the accompanying drawings, and to the letters of reference marked thereon.

Figure 1 is a view of a wash-boiler, partly in elevation and partly in section, with my improvements attached;

Figure 2 is a vertical transverse section thereof;

Figure 3 is a longitudinal section on line x x of fig. 2; and

Figure 4 is a perspective view of the spreader.

Corresponding letters refer to corresponding parts in the several figures.

The nature of my invention consists in providing an apparatus to be inserted in a wash-boiler, for the purpose of conducting the heated water from the bottom of the boiler to its top, and into the clothes; and

It consists in a partition, by which the conduit may be divided into two compartments, and also, in the combination of such partition with a spreader, as will be hereinafter described.

To enable those skilled in the art to make and use my invention, I will proceed to describe its construction and operation.

A, in the drawings, represents an ordinary wash-boiler, in which the flat tube or conduit B is placed, resting on legs, b. The tube may be made of tin, and of such dimensions, that when inserted in the boiler, it extends from end to end of the same, dividing it into two compartments, of about equal size, for such distance as it extends upward, its upper end being some distance below the top of such boiler. It is made of such width as is found desirable.

Its lower end is provided with curved flanges, B', forming a false bottom, the outer and lower edges being a little distance above the bottom of the boiler, so that the water may flow freely under it. Soldered to

the upper or convex surface of the flanges, near the tube, are the ends of the spider-legs b, extending in a horizontal direction to just beyond the outer edge of the flanges, when they are bent downward and under them, to form the feet.

It will be seen that a grate is thus formed above the flanges or false bottom, on which the clothes will lie, and be prevented from packing so as to obstruct the passage of water under the bottom.

C represents an angular V-shaped piece of tin inserted in the upper end of the flat tube, extending from end to end of the same, with its pointed end downward, and having for its object to spread the water over the sides of the tube as it rises, and let it fall on the clothes on each side of the same.

D represents a partition, which may be inserted in the tube, to divide it into two compartments longitudinally. It slides in guides on the inner curved sides of the tube, and consists of a sheet of tin, to the upper end of which is soldered a V-shaped piece, so that, as the liquid rises, it will be forced outward, over the sides of the tube. This partition is used when it is desirable to keep the water or other liquid on one side of the boiler from intermingling with that on the other side, to accomplish which, the lower end of the partition is made to reach down to the bottom of the boiler. When this partition is used, the spreader C is removed.

Having thus described my invention,

What I claim, and desire to secure by Letters Patent, is—

The combination of the partition D, spreader C, and tube B, substantially as herein shown and described.

In testimony whereof, I have signed my name to this specification, in the presence of two subscribing witnesses.

JOHN H. ELWARD.
